(57) **CLAIM**

The ornamental design for a sample collection kit, as shown and described.

DESCRIPTION

FIG. 1 is a top, front perspective view of a sample collection kit with the cap in an open configuration.

FIG. 2 is a top, back perspective view thereof.

FIG. 3 is a top, front perspective view thereof in a closed configuration.

FIG. 4 is a top, back perspective view thereof.

FIG. 5 is a front view thereof.

FIG. 6 is a back view thereof.

FIG. 7 is a top view thereof.

FIG. 8 is a bottom view thereof.

FIG. 9 is a right side view thereof; and,

FIG. 10 is a left side view thereof.

The dashed lines in the drawings depict portions of the sample collection kit that form no part of the claimed design. The dot-dash lines in the drawings depict symbolic break lines. The break lines and any appearance of features between the break lines form no part of the claimed design.

1 Claim, 7 Drawing Sheets
